CLAIM

We claim an ornamental design for the LED headlight, as shown and described.

DESCRIPTION

FIG. 1 is a perspective front view of a driver side LED headlight, the passenger side being a mirror image thereof. FIG. 2 is a front view of the driver side LED headlight, the passenger side being a mirror image thereof.

FIG. 3 is a side elevation view of the driver side LED headlight, the passenger side being a mirror image thereof; and,

FIG. 4 is a top plan view of the driver side LED headlight, the passenger side view being a mirror image thereof. Portions of the drawings shown in broken lines are for illustrative purposes only and form no part of the claimed design.
